IGNITER FOR EXPLOSIVE-ENGINES.

1,109,829.

Specification of Letters Patent.

Patented Sept. 8, 1914.

Application filed January 2, 1914. Serial No. 809,843.

To all whom it may concern:

Be it known that we, RAYMOND D. GORDON and LEE O. HUDSON, citizens of the United States, residing at Tulsa, in the 5 county of Tulsa and State of Oklahoma, have invented certain new and useful Improvements in Igniters for Explosive-Engines, of which the following is a specification.

10 This invention relates to improvements in igniters for gas engines of the class known as "tube igniters," in which the ignition is effected by admitting the explosive mixture of the motor to a tube heated to incandescence.

15 The especial object of our present improvements is to provide an igniter with means for automatically controlling the supply of gas to the burner from which the 20 ignition tube is heated, so that if the temperature of the igniter goes below a pre-determined point, the gas-supply to the burner will be at once increased, thereby maintaining a standard efficiency.

25 A further object of our invention is to provide means for controlling the area of the igniter tube which will receive the maximum application of heat from the burner.

30 In carrying out the foregoing and other objects of utility, we utilize the igniter tube as a thermostat and thereby control, through a series of adjustable levers, a gas-control valve, and we provide an adjustable member to the burner, and present these features in a preferred form in the accompanying drawing which forms a part of this application, and in which the single figure represents a view, partly in elevation and partly in section of a device embodying our 35 complete invention.

40 Referring to the details of the drawing, the reference character 1 represents a short piece of pipe leading from a suitable supply of gas and leading to one side of a globe valve casing 2, provided with a valve port 2^a upon which is adapted to be seated a valve 3 having an upwardly extending stem 3^a which is surrounded with an expansion coiled spring 4, adapted to exert sufficient 45 pressure on valve 3 to keep it from chattering. The spring and valve stem are partially inclosed by a cylinder 5, which is screwed into the top of the valve casing 2, and provided with a cap 5^a at its upper end 50 through which the valve stem extends. The end 3^b of the valve stem is loosely connected

with the lower end of a rod 6 by a pin coupling 6^a which is threaded on the lower end of the rod 6. The upper end of the rod 6 is threaded as at 6^b to receive two nuts 7 60 and 8, respectively.

65 To the exit opening of the valve casing 2, is connected a pipe 9 which leads to one end of a Bunsen burner tube 10, in which there are a series of holes 10^a controlled by a rotatable shoulder 10^b. Slidably fitted to the tube 10 is a sleeve 11, to the lower wall of which is secured a thumb screw 12, which extends downwardly and passes through a slot 13^a, provided in the lower wall of the 70 cylindrical burner casing 13. This casing is also provided with holes 13^b in its outer end and is secured at its inner end by bolts 13^c to the heater 14 at a point over an opening 14^a in the adjacent side wall of said heater. 75 The heater is cylindrical in form, and, at its lower end, is provided with a threaded boss 14^b, which screws into a heater base member 15, which may be secured in any suitable manner to the engine cylinder. The 80 boss 14^b is also interiorly threaded to receive a gland 16^b into which is screwed the lower end of the igniter tube 16, which communicates with the passageway 16^a in said gland and thereby with the interior of the base 85 15. The upper end of the tube 16 is internally threaded to receive the lower end of a thermostatic bar or rod 17, the upper end of which is extended at 17^a and extends above the top of the heater 14. The threaded stem 90 17^a is provided with a nut 18 which secures to the rod 17 a lever 19, the end 19^b of which is perforated to receive said stem 17^a. The lever 19 is fulcrumed at 20 on a bracket 95 20^a secured to the wall of the heater at the top and the long end of the lever is provided at its terminal 19^a with an opening which receives the threaded portion 6^b of the valve stem extension 6.

100 The operation of the device constructed substantially as above described will be obvious, but it might be well to state that the adjustment of the member 19 upon the valve extension rod 6 and the igniter tube extension 17, will be made by the operator so 105 that the valve 3 will be held off of its seat 2^a sufficiently to permit a predetermined quantity of gas to pass from the pipe 1 to the pipe 9 and thence through the burner 10 to the interior of the 110 heater 14. The shutter 10^b will be manually adjusted to provide the proper amount

of air to the burner 10 to balance the quantity of gas admitted through the valve casting tube. These adjustments will be determined upon the expansion of the rod 17 which in turn is controlled by the heat of the ignition tube 16, and the heat within the heater 14. Any variation in said temperature will result in the greater or less expansion of the rod 17, and hence the corresponding movement up or down of the end 19^b of the lever 19. As that end of the lever raises through the elongation of the thermostatic bar 17, the opposite end of the lever 19 will be lowered in the ratio represented by the relative lengths of the two arms of the lever, so that the spring 4 will act to lower the valve 3 toward its seat. Any lowering of the temperature in the heater 14 will cause a resulting shrinkage in the bar 17 so that the contractive action of the lever 19 on the spring 4 will be increased, thereby lifting the valve 3 with a resulting increase in the opening in the valve casing 2, through which the gas will pass from the tube or pipe 1 to the tube 9, and thence to the burner 10. It will be obvious also that the sleeve 11 is extended horizontally so that its inner end closely approaches the tube 16, the flame from said tube will be projected directly upon the walls of said tube, whereas if the tube is retracted to the position indicated in the drawing, the flame will spread and pass up the chimney or heater 14, so that the upper portion of the tube will be in the zone of greatest heat. By adjusting the tube 11 to the tube 10, therefore, we are able to regulate in measure the area of the

igniter tube 16, which will first become incandescent and thereby control the distance 40 which the gas must travel from the engine cylinder before it is ignited.

Having thus described our invention what we claim as new and desire to secure by Letters Patent, is:—

45

1. An igniter for explosive engines, comprising an ignition tube, a chimney surrounding said tube provided with an opening in its wall, a burner connected with said chimney and communicating with said opening, a pipe communicating with said burner, a valve adapted to control the gas passing through said pipe to said burner, and means connecting said valve with said ignition tube whereby said valve will be automatically 50 controlled by the heat in said chimney.

55

2. An igniter for explosive engines, comprising an ignition tube, a chimney surrounding the same and having an opening in its side walls, a casing secured to said chimney and communicating with said opening, an adjustable burner mounted in said casing, a gas supply pipe communicating with said burner, a valve controlling said pipe, a thermostat connected with said ignition tube, and means connecting said thermostat with said valve whereby the position of the valve is controlled by said thermostat.
